UNITED STATES PATENT OFFICE.

SAMUEL L. MARSDEN, OF NEW HAVEN, CONNECTICUT.

STONE-CRUSHER.

SPECIFICATION forming part of Letters Patent No. 230,304, dated July 20, 1880.

Application filed October 14, 1879.

To all whom it may concern:

Be it known that I, SAMUEL L. MARSDEN, of New Haven, in the county of New Haven and State of Connecticut, have invented a new and Improved Stone and Ore Crusher, of which the following is a specification.

Figure 1 is a sectional longitudinal elevation on line *x x*, Fig. 2. Fig. 2 is a transverse sectional elevation on line *y y*, Fig. 1. Fig. 3 is a transverse sectional elevation on line *z z*, Fig. 1.

Similar letters of reference indicate corresponding parts.

The invention relates to that class of crushers which operate with a reciprocating moving jaw or jaws.

The invention consists in constructing a vertical-jawed ore-crusher with an adjustable pitman, friction driving-pulleys, toggle-lever, toggle, and jaw-plates, as hereinafter set forth, so as to increase the efficiency, durability, and convenience of the machine.

In the drawings, A represents the crusher-frame, and B the crank-shaft, supported in the journal-boxes C C, and carrying on one end the fly-wheel D and on the other end the fly-wheel D' and the friction driving-pulley E, which latter is thrown in gear with the fly-wheel D' by means of the screw F, and thrown out of gear, so as to run as a loose pulley, by loosening the said screw F.

Stone and ore crushers have been run with a fast and a loose pulley on the crusher-shaft and a pulley of corresponding width on the engine or driving shaft; but such device is more expensive and absorbs more power and is less compact and convenient than the arrangement herein shown.

G is the rigidly adjustable pitman that connects the crank-shaft B with the lever-toggle H, and through or by which the motion of the said crank-shaft B is transmitted to the operating part of the crusher.

In the lever pattern, Blake's crusher, the only adjustable part by which the distance between the jaws at the bottom can be regulated is a wedge operated by a screw-nut that can be raised or lowered between the crusher-frame and the rear toggle-block, so that it can move said toggle-block forward or back an inch, or thereabout; but this limited

range of adjustment soon ceases to compensate for the wear on the jaws or jaw-plates, on the toggles, or on the end of the lever or the lever-bearing; hence some of these parts 55 in some instances require frequent renewal in order to restore the crusher to its normal working condition.

In a more recent pattern of Blake's crusher a like wedge fixed between the frame and the 60 toggle-block is the chief agent for the adjustment of the wearing parts.

In neither of these cases is the pitman of the crusher adjustable in relation to any of the wearing parts named, it being adjustable only 65 by means of a beveled key or keys, that may be made to move the crusher-journal brasses as they wear under the action of the crank-shaft.

The adjustable pitman G herein shown is 70 composed of two parts that screw together, so that it can be made longer or shorter at will, and at the same time always preserve the absolute rigidity that is essential to the proper working of the crusher. To compensate at 75 any time for the wear on the wearing parts of the crusher the two parts of this pitman G may be partially unscrewed from each other, and when the worn parts of the crusher are renewed the pitman may be shortened by screwing 80 together its parts to its primary condition.

H is the toggle-lever, whose long horizontal arm is connected to the crank-shaft B by the pitman G. A pin, a, that passes through the slotted holes b in the sides of the crusher-frame A and through the ear c of the lever H itself, forms, in combination with the toggle-block I, the fulcrum of the said lever H. In the face of the enlarged head of the toggle-lever H is a deep horizontal groove, d, having outward-curving edges, and opposite, in the back of the movable jaw K, is a similar groove, f. Set between the head of the lever H and the movable jaw K, and with an end resting in each groove d f, is the toggle L.

K is the movable jaw, that swings on a shaft, N, which rests in the boxes O on the sides of the frame A.

P is the fixed jaw, that is secured to the frame A.

Q Q' are the removable jaw-plates between which the ore or other substance is crushed.

The plate Q is held in place partly by the studs *g*, that project from the movable jaw K, and partly by the screw-bolt *h*, while the plate Q' is held in place by the cheek-plates R R 5 and the studs *g'*, that project from the jaw P and enter the inclined sockets *i i'*. These sockets *i i'* are intended to be inclined in both plates in opposite directions, so that they will serve the purposes for which they are designed 10 whichever end of the plates Q Q' be set up-
permost in the crusher. The purposes of these sockets *i i'* are primarily to assist in se-
curing the plates Q Q' in position, and, sec-
ondly, to afford good holds for hooks that may 15 be inserted to lift the said plates to or from
their positions. By these means the plates Q
Q' can be set in place or removed without the
usual risk of accident.

T is a wedge, vertically movable by means 20 of the thumb-screw *k*, for the purpose of ad-
justing the toggle-block I, to compensate in a
measure for the wear on the wearing part of
the crusher.

In many of the crushers now in use in which 25 motion is given to the movable jaw through
the medium of toggles it will be observed that
the said toggles are never brought in a straight
line with each other at any part of the stroke,
and that consequently the full power of the
30 applied force is not developed. In the crusher
herein described, however, the toggle is thrust
straight out in a horizontal line at the end of
the stroke, so that a most positive and un-
yielding pressure is exerted by the movable
35 jaw K upon the material to be crushed. The
spring S serves to retract the jaw K after
every forward motion.

In other crushers the toggles are never in a
straight horizontal line when they exert their
40 maximum force; hence at that instant a severe

backward thrust or pressure is always trans-
mitted to the crank-shaft as it is on a dead-
point, turning the center, thereby causing un-
due strain and wear upon the bearing-points
of the said crank-shaft, as well as upon the 45
bearings of the attached pitman. In this im-
proved machine, however, when the crank-
shaft is on a center and the toggle is simulta-
neously exerting its greatest force the said
toggle is in a straight horizontal line, so that 50
no back pressure or thrust is at that moment
transmitted to the bearings of the pitman or
shaft. Consequently the ordinary wear and dis-
tortion of these points is in a great measure
avoided.

I do not claim, broadly, an adjustable pit-
man for a stone-breaker.

Having thus described my invention, what
I claim as new, and desire to secure by Let-
ters Patent, is—

1. In an ore-crusher or stone-breaker, the
adjustable pitman G, constructed in two parts
that screw together, in combination with the
crank-shaft B, lever H, and toggle L, sub-
stantially as herein shown, and for the pur- 65
pose described.

2. The toggle-lever H, having an enlarged
head with ear *c* and groove *d*, in combination
with the toggle-block I, toggle L, and mov-
able jaw K, all constructed and arranged as 70
shown and described.

3. In an ore-crusher, the movable plates Q
Q', provided with inclined sockets *i i'*, in com-
bination with the crusher-jaws, substantially
as and for the purposes described.

SAMUEL LOWE MARSDEN.
